JILLSON & WHINFIELD.

Bleaching Fibrous Material.

No. 18,204.

Patented Sept. 15, 1857.

INVENTORS:
J. Jillson
Henry Whinfield

UNITED STATES PATENT OFFICE.

JULIUS A. JILLSON, OF POUGHKEEPSIE, AND HENRY WHINFIELD, OF NEW YORK, N. Y.

METHOD OF TREATING FIBROUS OR TEXTILE SUBSTANCES IN A VACUUM FOR CLEANSING PURPOSES.

Specification of Letters Patent No. 18,204, dated September 15, 1857.

To all whom it may concern:

Be it known that we, JULIUS A. JILLSON, of the city of Poughkeepsie, county of Dutchess, and State of New York, and 5 HENRY WHINFIELD, of the city, county, and State of New York, have invented a new and useful Method of Treating Various Materials or Substances in a Permanent Vacuum for Washing, Bleaching, and Analogous Purposes; and we do hereby declare that the 10 following is a full, clear, and exact description of the same, reference being had to the annexed drawings, making a part of this specification and representing an apparatus 15 adapted for carrying out this method in which—

Figure 1 is an elevated perspective view and Fig. 2 is an elevated sectional view.

The same letters have reference to the 20 same parts in each view.

The nature of our invention consists in performing the method above mentioned or any other analogous to it either with or without heat in a permanent vacuum. The 25 air being removed the substances or materials treated expand and become readily impregnated with the liquid and easily impart their soluble properties either of dirt, gum, &c., to the fluid with which they are 30 treated and at low temperatures suitable to their various colors and different qualities to be employed, by which means over heating and the continued wear and tear by rubbing, pounding, and wringing, is prevented, and great saving of time realized.

Using a permanent vacuum in all the chambers of the apparatus we employ for treating the various substances or materials or other analogous operations, and as 40 through the entire operation the absence of the air allows free passage to any fluid or gas we may employ, the said fluid or gas is rotated continuously in a vacuum by a double or single acting force pump working 45 in said vacuum without variation or receiving any assistance of force from said vacuum and at temperatures required by the nature of the colors and of the materials or substances treated, and the purpose of the 50 operation performed.

To enable others skilled in the art to use our said method we will proceed to exemplify its application.

The apparatus may be constructed of any

suitable materials such as brass, copper, iron 55 galvanized, tin, or wood.

A, is a receiver with an air tight cover B, screwed down air tight by the set screw C, or in any other suitable way. The said receiver A, is placed over the furnace or lamp 60 G. In the receiver A, is placed a strainer D, and over it a detached receiver E, with a similar strainer F. The said receiver A, is connected by the pipes N, O, and P, or their equivalents with the double or single acting 65 force pump I.

T, is a chamber containing a glass cup or jar W, for holding the bleaching or disinfecting gas or liquid, its cover U, screwed down thereon is connected with the upper 70 part of the force pump I, by the pipe X, provided with a stop cock Y, and by the pipe P.

a, a, a, are pipes passing through under and between the receiver A, and the furnace 75 or lamp G, to admit air, when heated air may be required, for drying, or draining, the contents of said receiver A, or E, or any purpose. These pipes deliver the air into and at the top of receiver A, at b.

c, is a cock to shut off the air when not required.

The strainiers D, and F, are made of 80 perforated copper, brass, or wire or woolen cloth, paper, sponge or equivalent.

One or more receivers similar to A, and with one or more double or single acting force pumps and when extensive and large receivers or apparatus are required having one or more pumps for exhausting the air 90 and forming a vacuum may be employed. Also one or more pumps for rotating and forcing the gas or fluid through and through the various substances or materials may be used and can be worked by hand or driven 95 by any other power.

Having thus constructed an apparatus as described or any other equivalent thereto as may be required, we place the wearing apparel, textile, or fibrous fabrics, animal or 100 vegetable wools, silks, rags, or any other material or substance to be treated in the upper part of the receiver A, or the inner detached receiver E and the liquid necessary either cold or hot in the lower part of said receiver 105 A, under the strainer D, at a degree of heat that will not injure the materials or substances to be treated and closing the cover

B, air tight and having all the stop cocks closed except R, and J, let the force pump I, be set in motion. The air being drawn out of the apparatus, a vacuum will be attained in all its chambers, a thermometer being fixed to said receiver A, if required, any desired degree of heat can be obtained by the use of said furnace or lamp G, or other equivalents. If then the stop cocks R, and 5 J, be closed and stop cocks Q, and S, opened and the motion of the pump continued the liquid contained in the receiver A, will be drawn out therefrom in and passing through the pipe N, and valve L, through the said 10 pump I, through the pipe P, and valve M, into the top of the receiver A, it will return through the materials or substances treated to the lower part of receiver A, and thus be rotated by the said pump for any length of 15 time in an equal temperature with great force and velocity over and over through and through the said materials or substances contained in said receiver A, or inner detached receiver E, until in a very short time the 20 dirt or gum is extracted or cleansed from the said materials or substances treated. If the stop cock R, Q, and J, be opened and the 25 stop cock S, closed, and the motion of the pump continued, air may be drawn from the lower part of receiver A, and forced into 30 the upper part of said receiver and through and through the materials or substances treated until the same be thoroughly dried, the action of the air drawing all the liquid 35 into the bottom of receiver A, when the saturated fluid or refuse may be drawn off by the discharge cock H. The apparatus can then be opened the contents removed and cleansed for another operation.

40 There may be attached to the apparatus as shown by letter T, a chamber or vessel with pipes connecting it to the receiver A, for the purpose of generating and passing into said receivers A, and E, bleaching or 45 disinfecting gases or liquids which operation being performed in a vacuum forms an essential feature of our method. By closing the stop cocks J, R, and S, the said gases or liquids will be permitted to escape from 50 chamber T, by the pipe X, and if then the stop cocks R, Y, and Q be opened and the pump be set in motion the said bleaching or disinfecting gases or liquids will be drawn from the chamber T, and forced through 55 and through the materials or substances treated over and over and in a vacuum until in a short time the contents of said receivers A or E, will on account of the absence of

the air be perfectly bleached or disinfected. By subsequently closing the stop cocks J, K, 60 Q and S, the said bleaching or disinfecting gases or liquids can be nearly all forced back into the chamber T, this, owing to the absence of the air in a comparatively pure state where they may be retained by closing the 65 stop cock Y, until wanted again. The receiver A, can then be opened and contents removed. The said wearing apparel textile or fibrous fabrics, animal or vegetable wools, 70 silks, rags, or any other materials or substances after they have passed through the process or operation of cleansing or bleaching in a vacuum can all be rinsed without removal from the receiver A, in a vacuum by our method as before detailed. 75

It is evident that this method is applicable to various other purposes such as extracting, filtering and draining and which may be performed in a vacuum.

The permanent vacuum forms the essential 80 feature in our method as heretofore described and in consequence of the use of a vacuum in combination with a force pump dispensing with the use of sand and the tedious and uncertain process of maceration and percolation until in a short operation as before detailed a perfectly saturated solution with a small quantity of fluid is obtained in fact the whole strength of the principle is extracted from the woods, roots, leaves, grain, 85 seeds, or other materials or substances either medicinal or otherwise that may be used and with the saving of great expense in evaporating large quantities of liquid in the vacuum pan. 90

It is also evident that machines or apparatus may be constructed different from the one here described and differently arranged keeping the main feature of our method and objects in view as heretofore described and illustrated. 100

Having now described and fully set forth our invention and illustrated our way of carrying it out, what we claim as new and desire to have secured to us by Letters Patent is— 105

The process of treating fibrous and textile substances in a permanent vacuum for extracting coloring, grease or other foreign matters substantially as set forth.

J. A. JILLSON.
HENRY WHINFIELD.
